UNITED STATES PATENT OFFICE.

LUIGI ANGIULLI, OF NEW YORK, N. Y.

SIGNAL APPARATUS.

1,323,517.

Specification of Letters Patent.

Patented Dec. 2, 1919.

Application filed April 15, 1918. Serial No. 228,595.

To all whom it may concern:

Be it known that I, LUIGI ANGIULLI, residing at the city of New York, borough of Manhattan, in the county and State of New York, have invented certain new and useful Improvements in Signal Apparatus, of which the following is a full, clear, and exact specification.

This invention relates to improvements 10 in signal apparatus, and has for its object to provide an apparatus which is simple in construction and operation, and by means of which a continuous audible signal can be produced.

15 Further, said invention has for its object to provide a signal apparatus the parts of which may be quickly and readily assembled.

Further, said invention has for its object 20 to provide a signal apparatus which is compact in form, capable of being inexpensively made, and which consists of but few parts so constructed and arranged as to be readily assembled.

25 Further, said invention has for its object to provide a signal apparatus comprising a shell, a diaphragm and diaphragm actuating means rotatably mounted upon a member fixedly supported upon the shell.

30 Further, said invention has for its object to provide a signal apparatus comprising a diaphragm, a two-part shell having a tie-rod to hold the parts assembled, and diaphragm actuating means rotatably mounted 35 upon the tie-rod.

Further, said invention has for its object 40 to provide a signal apparatus casing comprising a shell consisting of a plurality of parts suitably maintained in assembled position, and a resonator carried by the shell.

Other objects will in part be obvious and in part be pointed out hereinafter.

To the attainment of the aforesaid objects 45 and ends my invention consists in the novel details of construction, and in the combination, connection and arrangement of parts hereinafter more fully described and then pointed out in the claims.

50 In the accompanying drawing showing an illustrative embodiment of the invention,

Figure 1 is a plan view of a signal apparatus constructed according to and embodying the invention;

Fig. 2 is a sectional view taken substantially on the line 2-2 of Fig. 1;

Fig. 3 is a sectional view taken substantially on the line 3-3 of Fig. 2, and

Fig. 4 is a sectional view taken substantially on the line 4-4 of Fig. 2.

Referring to the drawing 10 indicates a shell consisting of two parts 11 and 12 held in assembled relation by a tie member comprising a tie-rod 13, having threaded ends extending through perforations formed in the side walls of the shell parts 11 and 12 and carrying nuts 14. The inner edge of the part 11 is offset slightly, as indicated at 15, to form a recess to receive the inner edge of the part 12 whereby a close fitting joint is provided in order to prevent dirt or moisture from entering the shell. The side walls of the shell parts 11 and 12, which are substantially parallel to one another 70 throughout the greater portion of the shell, are flared outwardly at their front portions, as indicated at 15', to form a circular opening for the shell, and are provided with inwardly extending arc-shaped flanges 16 80 to which an annular plate 17 is secured by bolts 18. 19 indicates a resonator provided at its rear end with an outwardly-extending flange 20 registering with the annular plate 17 and secured thereto by bolts 21. 85

Clamped between the annular plate 17 and the flange 20 of the resonator 19, is a diaphragm 22, preferably formed of sheet metal, provided at its center with a threaded bushing 23 within which is adjustably mounted a wear member 24, consisting of a threaded pin having its inner end beveled or pointed. The wear member is held in its adjusted position by means of a locknut 25 threaded upon its outer end. 95

Rotatably mounted upon the tie-rod 13 is a diaphragm actuator, which is shown as comprising a fly wheel 26 and a disk 27 provided with peripheral teeth 28 adapted to engage the inner end of the wear member 24. A spring-pressed pawl 29, carried by the diaphragm actuator 26, 27 engages the teeth of a pinion 30 rotatably supported upon the tie-rod 13. This construction insures the rotation of the diaphragm actuator 105 26, 27, when the pinion 30 is rotated in one direction, and permits the pinion to rotate in the opposite direction without rotating the diaphragm actuator. In order to maintain the pinion 30 and the diaphragm actuator 110

ator 26, 27 properly positioned upon the tie-rod 13 and to protect the walls of the shell 10 against wear, a washer 31 is positioned upon the tie-rod 13 between the pinion 30 and the wall of the shell part 11, and a bushing 32 is positioned upon the tie-rod 13 between the diaphragm actuator 26, 27 and the wall of the shell part 12.

A guide member 33, carried by the shell 10, has its lower end secured thereto adjacent the bottom thereof and has its upper end projecting through the top wall of the shell 10. Reciprocatingly mounted within the guide member 33 is a plunger 34 provided with a plurality of teeth 35 constituting a rack and engaging the pinion 30. The plunger 34 is normally maintained raised by means of a spring 36 having one of its ends fastened to a bracket 37 secured to the shell 10 and having its other end engaging a stop 34' carried by the plunger 34. Secured to the upper end of the plunger 34 is a head 38 adapted to be engaged by the hand in order to depress the plunger 34 when the horn is to be operated. As shown, the head 38 rests upon the upper end of the plunger 34 and is held in place thereon by an upwardly extending reduced portion 39 which extends through a correspondingly-shaped perforation in the head 38 and has its upper end headed to engage the head 38.

To operate the horn the plunger 34 is pressed downwardly by the hand of the operator thereby causing the rack 35 to rotate the pinion 30, and, as the pinion 30 is then rotated, the diaphragm actuator will also be rotated by reason of the engagement of the spring pressed pawl 29 with the pinion 30. As the diaphragm actuator 26, 27 rotates the teeth 28 on the periphery of the disk 27 will successively engage the inner end of the wear member 24 carried by the diaphragm 22 thereby causing the diaphragm 22 to vibrate and produce an audible signal. Upon removing the pressure of the hand from the head 37 of the plunger 34, after it has been depressed to its lowermost position, the spring 36 will raise the plunger 34 to its normal position. During this upward movement of the plunger 34 the pinion 30 will be rotated in the opposite or reverse direction to that in which it was rotated by the depression of the plunger 34, but the rotation of the pinion 30 in such reverse direction will have no effect on the rotation of the diaphragm actuator 26, 27, as the spring pressed pawl 29 will ride over the teeth of the pinion 30. The diaphragm actuator 26, 27, is therefore free to rotate upon the tie-rod 13, and, by reason of the momentum of the fly wheel 26, it will continue to rotate during the time that the plunger 34 is being returned to its nor-

mally raised position by the spring 36. It will thus be understood that by quickly and successively depressing the plunger 34 and allowing it to return to its normal position a number of times, a continuous signal can be produced.

Having thus described my said invention what I claim and desire to secure by Letters Patent is:—

1. In a signal apparatus, in combination, a shell comprising a plurality of parts, means for holding said parts in assembled position, a sound producing element operatively associated with said shell, means for actuating said sound producing element supported upon said holding means, and means for operating said actuating means, substantially as specified. 75

2. In a signal apparatus, in combination, a shell comprising a plurality of parts, means for holding said parts in assembled position, a sound producing element operatively associated with said shell, means for actuating said sound producing element movably supported upon said holding means, and means for operating said actuating means, substantially as specified. 80

3. In a signal apparatus, in combination, a shell comprising a plurality of parts, means for holding said parts in assembled position, a sound producing element operatively associated with said shell, means for actuating said sound producing element rotatably supported upon said holding means, and means for operating said actuating means, substantially as specified. 95

4. In a signal apparatus, in combination, a shell comprising a plurality of parts, a tie-member for holding said parts in assembled position, a sound producing element operatively associated with said shell, means for actuating said sound producing element rotatably supported upon said tie-member, and means for operating said actuating means, substantially as specified. 100

5. In a signal apparatus, in combination, a shell comprising a plurality of parts, a tie rod extending through said shell transversely thereof for holding said parts in assembled position, a sound producing element operatively associated with said shell, means for actuating said sound producing element supported upon said tie-rod, and means for operating said actuating means, substantially as specified. 110

Signed at the city of New York, in the county and State of New York, this 27th day of February, one thousand nine hundred and eighteen.

LUIGI ANGIULLI.
